UNITED STATES PATENT OFFICE.

SAMUEL EWART, OF LONDON, ENGLAND.

DESIGN FOR A VENTILATING-COWL.

41,810.

Specification for Design. Patented Sept. 26, 1911.

Application filed July 29, 1910. Serial No. 574,577. Term of patent 14 years.

To all whom it may concern:

Be it known that I, SAMUEL EWART, a subject of the King of Great Britain, residing at 346, 348, and 350 Euston road, London, England, have invented a new, original, and ornamental Design for Ventilating-Cowls, of which the following is a specification, reference being had to the accompanying drawing, forming part thereof.

Figure 1 is an elevation of a cowl show-

ing my new design. Fig. 2 is a plan view thereof.

I claim:

The ornamental design for a ventilating cowl as shown.

SAMUEL EWART.

Witnesses:

C. G. REDFERN,
A. ALTUST.
